UNITED STATES PATENT OFFICE.

JOHN T. PARKER, OF FARMINGTON, MAINE.

IMPROVED WELL-BORER.

Specification forming part of Letters Patent No. 58,672, dated October 9, 1866.

To all whom it may concern:

Be it known that I, JOHN T. PARKER, of Farmington, Franklin county, State of Maine, have invented a new and Improved Self-Expanding Auger for Boring Artesian Wells; and I do hereby declare that the following is a full, clear, and exact description thereof, which will enable others skilled in the art to make and use the same, reference being had to the accompanying drawings, forming part of this specification, in which—

Figure 1 is a front view of my improved expanding auger, and Fig. 2 is a bottom view of the same.

Similar letters of reference in the different figures indicate corresponding parts.

This invention relates to that class of auger in which the tubing of the well is made to follow immediately in the rear of the auger, and, owing to its expanding and contracting construction, the auger may be removed at pleasure through the bore of the tubing, and it consists in a pod-auger divided into two parts, and hinged together in such a manner that when boring the auger is expanded by the resistance of the material which is being bored or acted upon, as hereinafter explained.

This auger in general form is much like an ordinary pod auger; but the body of the auger is divided into two parts, A, B, Fig. 1, and these two parts are hinged together by a hinge or pivot, c, and are also connected together by a stop-pin, e, which projects from the part A, and works in a slot, d, in the other portion, B, so that the lower portions of the two parts A and B may spread apart or expand more or less, as determined by the length of the slot d, and then the pin e acts as a stop to prevent

further expansion of the auger. b is the cutting-lip, and a is the gage-lip, which prevents the cutting-lip b from taking too rank a hold or bite. A shows the tubing following immediately in the rear of the auger. A' is the driving-shank of the auger.

Its operation is as follows: The auger when contracted drops down readily through the bore of the pipe or tubing D; but when it strikes the ground and boring is commenced, then the cutting-lip b takes hold, and the resistance of the substance being cut presses b outward, so that the auger is expanded until stopped by the pin or stop e, and the auger in this position makes a cut, the diameter of which is equal to the outside diameter of the tubing D, and as the boring progresses the said tubing D is made to follow in the rear of the auger A B. When the auger is to be withdrawn through the tubing D it contracts readily as soon as its cutting-edge b is raised clear of the bottom of the bore, so that the cutting-lip lets go its hold; or the auger may be contracted by reversing.

By these means I produce an expanding auger which is efficient in action, and which is extremely simple in its construction.

Having thus described the nature of my invention, what I claim as new, and desire to secure by Letters Patent, is—

The combination of the slotted part B, part A, stop-pin e, and hinge c, operating substantially as described, for the purpose specified.

JOHN T. PARKER.
